(57) **CLAIM**

The ornamental design for a safety cone with retractable legs, as shown and described.

DESCRIPTION

FIG. 1 is a right-rear perspective view of the safety cone with retractable legs, showing the new design with the legs in the extended position;

FIG. 2 is a front view of the safety cone with retractable legs with the legs in the extended position;

FIG. 3 is a rear view of the safety cone with retractable legs with the legs in the extended position;

FIG. 4 is a right view of the safety cone with retractable legs with the legs in the extended position, the left view being a mirror image thereof;

FIG. 5 is a top view of the safety cone with retractable legs with the legs in the extended position;

FIG. 6 is a bottom view of the safety cone with retractable legs with the legs in the extended position;

FIG. 7 is a right-rear perspective view of the safety cone with retractable legs, showing the new design with the legs in the retracted position;

FIG. 8 is a front view of the safety cone with retractable legs with the legs in the retracted position;

FIG. 9 is a rear view of the safety cone with retractable legs with the legs in the retracted position;

FIG. 10 is a right view of the safety cone with retractable legs with the legs in the retracted position, the left view being a mirror image thereof;

FIG. 11 is a top view of the safety cone with retractable legs with the legs in the retracted position; and,

FIG. 12 is a bottom view of the safety cone with retractable legs with the legs in the retracted position.

Portions of the safety cone with retractable legs shown in broken lines are illustrative only and form no part of the claimed design.

1 Claim, 9 Drawing Sheets
